Attorneys.

UNITED STATES PATENT OFFICE.

DAVID CROWNFIELD, OF CAMBRIDGE, MASSACHUSETTS.

LIGHTING-FIXTURE.

1,265,885.

Specification of Letters Patent. Patented May 14, 1918.

Application filed December 4, 1916. Serial No. 134,818.

To all whom it may concern:

Be it known that I, DAVID CROWNFIELD, a citizen of the United States, and resident of Cambridge, in the county of Middlesex and 5 State of Massachusetts, have invented new and useful Improvements in Lighting-Fixtures, of which the following is a specification.

This invention relates to lighting fixtures 10 adapted to be used either on a wall, ceiling or with a table lamp, and more particularly the invention relates to a lighting fixture for use on the wall of a hospital ward.

It has been found desirable in many places 15 to illuminate a limited region without radiating light in any appreciable measure outside of the limited area. This is particularly true in hospital wards containing a number of beds, inasmuch as it is frequently necessary to illuminate one bed or the immediate 20 region thereof without projecting much if any light to other portions of the room. For example, it is necessary to illuminate the region surrounding one patient for purposes 25 of examination by a physician or attendant, by a nurse, for reading purposes, etc., at all hours of the night.

The principal object of my invention is to provide a light fixture which will illuminate 30 a limited region without radiating substantially any light outside of the limited region, and more particularly to illuminate the region indirectly by throwing light on a wall or other area adjacent the region. Another 35 object is to provide means whereby the light may be quickly and easily shifted from one area to another so as to be readily adjusted to the proper zone. A further object is to provide apparatus of the character 40 referred to which has smooth, continuous, rolling, non-dust catching external surfaces, thereby affording no places for the lodgment of dust and germs, and the attainment of this end by concealed mechanism. And still 45 a further object is to provide improved means for attaching the lamp and shade support to the supporting bracket or other supporting means, and to attain the above mentioned advantages by strong, rigid and 50 durable construction protecting the lamp and the interior of the shade from dust and dirt.

Other objects of the invention will be apparent from the following description 55 taken with the accompanying drawings, in which—

Figure 1 is a vertical longitudinal section

of the lighting fixture, parts being shown in elevation;

Fig. 2 is a bottom plan view of the fixture; 60

Fig. 3 is a bottom plan view showing the screening globe rotated in one direction;

Fig. 4 is a bottom plan view of the fixture showing the screening globe rotated in the other direction; and 65

Fig. 5 is a detail sectional view of improved means for attaching the lamp and shade support to the wall bracket.

In the particular embodiment of the invention herein disclosed, the fixture is illustrated as being applied to a wall support, this being the preferred form of the invention. The apparatus comprises a hollow supporting stem 1 connected to the supply conduit through the medium of the hickey 70 joint 2 and the insulating joint 3, a bell-shaped canopy 4 being threaded on the stem 1 so as to house the connecting joints and so as to form a smooth continuous seamless joint at 6 with the support stem 1, all as 75 more fully disclosed in my former Patent No. 1,112,197, granted September 29, 1914.

The outer end of the stem 1 is bent downwardly and is provided with internal threads at its lower end into which is 80 threaded a nipple 7, the nipple also being provided with external threads on its lower end to support the lamp socket 8 and being provided with an axial opening to receive the supply wires. The nipple 7 is provided 85 with an enlarged central portion, preferably tapered on its outer surface so as to fit in the upper end of the bell-shaped shell 9. The upper end of the shell 9 is provided with an internal flange adapted to be clamped between the enlarged portion of the nipple and the end of the stem 1, the parts having such diameters as to form a smooth continuous joint at this point.

Instead of the lower end of bracket 1 100 being provided with an integral internal sleeve as illustrated in Fig. 1, a separate sleeve 10 may be employed, as illustrated in Fig. 5, the sleeve 10 being internally threaded, as is the integral sleeve in Fig. 1, 105 and also being brazed or otherwise secured in the lower end of bracket 1.

In accordance with the principal object of my invention, I provide a relatively opaque globe 11 entirely surrounding the light 110 source contained within the lamp bulb 12. The globe 11 is preferably made substantially spherical in contour, although other shapes may be employed within the scope

of my invention. On one side of the globe is provided a window surrounded by a struck-up flange 13, within which is adapted to fit a transparent closure 14, the latter being held in position by any suitable means, as for example by means of the clips 16. Thus, light is permitted to radiate from the light source only in a single lateral direction, and in order to increase the amount of light radiated through the window, reflecting means is preferably provided within the globe 11, and the reflecting means may, for example, comprise the interior surface 17 of the globe 11, the globe 11 preferably being of metal and the inner surface being polished and lacquered.

The globe 11 is mounted to rotate about the longitudinal axis of the lamp so that the light may be directed either directly on to the wall when in the position illustrated in Figs. 1 and 2 or obliquely to the wall on either side of the fixture as illustrated in Figs. 3 and 4. A suitable means for rotatably supporting the globe 11 comprises an annular collar 18 surrounding opening 19 in the upper end of the globe 11, the collar preferably being formed integrally with the globe and being folded outwardly as indicated at 21 and extended downwardly a part of the length of the collar 18 so as to rest on the forward ends of bearing screws 22, preferably three in number, which project inwardly through threaded openings in the lower end of the shell 9. The globe is secured to the shell 9 by withdrawing the set-screws 22 a sufficient distance to permit the insertion of the collar 18 within the lower end of the shell 9, after which they are advanced into such position as to be engaged by the out-turned flange 21 of the collar 18. Thus, the globe is held in position upon the screws 22 by engagement of the out-turned part 21 of the globe between the ends of the screws 22 and the reduced interior of the shell 9, the globe thus being free to be rotated through any desired angle but being otherwise firmly held to the shell 9.

In order to afford a smooth continuous external surface for the fixture an outer sliding cover 23 is preferably provided to surround and to be spaced away from the lower end of the supporting shell 9, thereby wholly to inclose the means for attaching the globe to the shell 9, that is the screws 22, in the embodiment of the invention herein illustrated. The central portion of the shell 9 is preferably made substantially cylindrical in contour and the lower end is preferably made bell-shaped in contour. The sliding cover 23 is adapted to slide vertically on the cylindrical portion of the shell 9, and is so shaped as snugly to fit the doubly curved portion of the bell-shaped end of shell 9 when in the normal full-line position. The lower end of the bell-shaped slid-

ing cover 23 is slightly flared outwardly so as to clear but to hold in locked position the heads of the screws 22, and it extends downwardly somewhat beyond the lower edge of the shell 9 so as either to contact with the globe 11 or to come into immediate proximity therewith when the sliding cover is seated upon the bell-shaped lower end of shell 9.

Considerable heat is developed in the globe 11 and shell 9, but it has been found in practice that sufficient venting of the expanding and contracting air included in these inclosures occurs around the collar 18 and between the screws 22 and the space between the shell 9 and sliding cover 23 even when, as intended, cover 23 seats snugly upon the globe 11 to provide a closure avoiding the entrance of dust and dirt into the globe 11. I attribute the observed good ventilation of the lamp in part to loosening of the sliding cover 23 due to expansion by the heat of the lamp when lighted in excess of the expansion of the less exposed upper cylindrical part of the shell 9.

Thus a lighting fixture is afforded which is adapted to be mounted at the head of a hospital bed in such manner as to reflect light from the wall of the room, which is usually reflective, and thereby indirectly illuminate the immediate region of a single patient without radiating light to other portions of the room. As indicated in Fig. 1 the axis of the lamp and globe is not exactly vertical, but is inclined outwardly and downwardly so that when the light is a short distance above the patient the light is deflected downwardly as it strikes the wall. If the lamp is on the right of the bed the globe may be rotated on the inclined bearing in shell 9 to the left to illuminate the patient and it may be rotated to the right to illuminate a table standing beside the patient, for example or turned farther around to illuminate a part of the room above the level of the light. The extent of the outward inclination of the light source depends upon its position with respect to the region to be illuminated, and likewise its exact size and its disposition in the globe depend upon the particular use to which the fixture is to be put; but a cardinal feature of the invention is the disposition of the window in a lateral portion of the globe, whether directly laterally of the light source or whether somewhat above or below the transverse plane of the light source, so that the direction of radiation may be regulated by rotating the globe around the light source. The construction is wholly free from exterior crevices for the lodgment of dust, as will be apparent.

I claim:

1. A lighting fixture supporting therein a light socket, and having a shell surround-

- ing said socket, a sliding cover having at one end a sliding engagement with said shell, in combination with a globe having a collar adapted to be received within said shell and 5 screws on said shell adapted to engage said collar to support said globe, said sliding cover in one position being spaced away from, surrounding and covering said supporting means.
- 10 2. A lighting fixture having therein a light socket, a shell surrounding said socket, a sliding cover having at one end a sliding engagement with said shell, in combination with a relatively opaque globe having a window 15 therein and having a collar adapted to be received within said shell, and screws on said shell adapted to engage said collar to support said globe for rotation therein, said sliding cover in one position being spaced 20 away from, surrounding and covering said supporting means.
3. A lighting fixture having therein a light socket, a shell surrounding said socket, a sliding cover having at one end a sliding engagement with said shell, in combination 25 with a relatively opaque globe having a window therein and a reflecting interior surface, and having a collar adapted to be received within said shell, and screws on said shell 30 adapted to engage said collar to support said globe for rotation, said sliding cover in one position being spaced away from the end of said shell and surrounding and covering said screws.
- 35 4. A lighting fixture having therein a light socket, a shell surrounding said socket, a sliding cover having at one end a sliding engagement with said shell, said shell, cover and the joint between them being of sweeping 40 contour free from lodgment places for dust, in combination with a globe having a collar adapted to be received within said shell, and screws on said shell adapted to engage said collar to support said globe, said 45 sliding cover in one position being spaced away from the end of said shell and surrounding and covering said supporting means.
5. In a depending lighting fixture, a globe extending around the light source, an annular shell surrounding one end of the light source, inwardly extending screws for attaching the globe to the annular shell and a cover surrounding the annular shell and 55 adapted to slide on the shell into engagement with the globe, the cover being spaced away from the shell at its lower end, and making a normally tight joint at an acute angle therewith at its upper end.
- 60 6. In a lighting fixture, in combination, means to support the fixture on the wall or ceiling, a wall canopy concealing the supporting means, a stem emerging from said wall canopy, a lamp socket attached to the stem, a shell concealing the socket having 65 screws at its lower extremity to exteriorly support a shade, and a sliding cover to conceal the screws and hold them locked when in supporting relation to the shade, the wall canopy, supporting stem, socket cover and 70 shell, sliding cover and shade all having a flowing non-dust catching outline and surface.
7. In a lighting fixture, in combination, means to support the fixture on the wall or 75 ceiling, a wall canopy concealing the supporting means, a stem emerging from said wall canopy, a lamp socket attached to the stem, a shell concealing the socket having screws at its lower extremity to exteriorly 80 support a shade, a closed continuous globe shade supported thereby, and a sliding cover to conceal the screws and hold them locked when in supporting relation to the shade; the wall canopy, supporting stem, socket 85 cover and shell, sliding cover and shade all having a flowing non-dust catching outline and surface.
8. A lighting fixture having therein a socket concealing member comprising an inner shell and an outer cover, the inner shell being formed to secure even, unbroken continuation with its supporting and abutting members, and its lower extremity having screws interiorly entering to outwardly 90 engage the neck of a supported shade, the outer cover being adapted to slide backward and forward over the inner shell and over the screws supporting the shade when they are positioned to support the shade, whereby to 95 hold them in locked position.
9. A lighting fixture having therein a socket concealing member comprising an inner shell and an outer cover, the inner shell being formed to secure even, unbroken continuation with its supporting and abutting members, and its lower extremity having screws interiorly entering to outwardly 105 engage the neck of a supported shade, the outer cover being adapted to slide backward and forward over the inner shell and over the screws supporting the shade when they are positioned to support the shade, whereby to 110 hold them in locked position, the outer shell having such relation to the inner 115 shell and the supported shade that when in its lowered position it will come to a dust-tight seat against the shade.

Signed by me at Boston this 29th day of November 1916.

DAVID CROWNFIELD.
